UNITED STATES PATENT OFFICE.

PHILIP HAAS, OF DAYTON, OHIO.

HYDRAULICALLY-OPERATED VALVE MECHANISM.

1,331,707.

Specification of Letters Patent. Patented Feb. 24, 1920.

Application filed August 19, 1919. Serial No. 318,513.

To all whom it may concern:

Be it known that I, PHILIP HAAS, a citizen of the United States, residing at Dayton, in the county of Montgomery and State of Ohio, have invented certain new and useful Improvements in Hydraulically-Operated Valve Mechanism; and I do hereby declare the following to be a full, clear, and exact description of the invention, such as will enable others skilled in the art to which it appertains to make and use the same.

My invention consists in the novel features hereinafter described, reference being had to the accompanying drawings which illustrate an embodiment of the invention selected by me for purposes of illustration, and the said invention is fully disclosed in the following description and claims.

Referring to the drawings,

Figure 1 represents a water closet installation containing an embodiment of my invention.

Fig. 2 represents a vertical central sectional view of my improved hydraulically operated valve mechanism showing the flushing valve in closed position.

Fig. 3 is a view similar to Fig. 2, showing the flushing valve in open position, a portion of the valve cover being shown in elevation.

Fig. 4 is a horizontal sectional view of the valve mechanism, a portion of the valve cover being shown in elevation.

Fig. 5 represents a vertical section on the line 5—5 of Fig. 1, looking in the direction of the arrows.

Fig. 6 is a section on line 6—6 of Fig. 1, looking in the direction of the arrows and showing the interior of the valve cover or cap.

Fig. 7 is a vertical section on line 7—7 of Fig. 1, looking in the direction of the arrows.

Fig. 8 is a section on line 8—8 of Fig. 1, looking in the direction of the arrows.

Fig. 9 is a detail view of the transfer tube for establishing communication between the inlet water passage of the back pressure chamber.

Fig. 10 is a detail of a modified form of device which may be used in place of the transfer tube.

My invention relates particularly to hydraulically operated flushing valves for water closets in which the opening and closing of the flushing valve mechanism is effected by water pressure. This type of valve

mechanism has always been used to the greatest advantage in buildings where a very high pressure and large volume of water is available for flushing purposes, making it possible to dispense with flush tanks and effecting the opening and closing of the valve by the pressure of the water, the opening of the valve, the flushing operation, the production of an after filling of the closet bowl, and the final closing of the flushing valve, all being effected in proper sequence by the action of the water pressure, without aid from or interference by the operator, who merely starts the cycle of operation by pressing a button, or otherwise. It has been found impracticable to use this type of valve mechanism in buildings in which the water supply pipes are of small diameter such as have been commonly furnished in the ordinary private house, and where the pressure of water in the main is comparatively low, for the reason that the required volume of water and the required high pressure of this large volume of water was not available, and without it the valve mechanism would not operate correctly. The use of this type of hydraulically operated valve has therefore been almost entirely limited to office buildings, hotels, apartment houses, and other large buildings, and their use in private dwellings has been negligible.

The object of my present invention is to provide a hydraulically operated flushing valve mechanism, adapted especially for use in private houses and other buildings in which the water supply is conveyed through comparatively small pipes, and at comparatively low pressures, so as to extend to the very large class of private dwellings, the use of this type of valve mechanism with its attendant advantages, and to secure the accurate predetermined operation of the valves under all ordinary conditions, with the same efficiency as is now obtained in installations in which the larger supply pipes and higher pressures are available. In the accompanying drawings I have illustrated one embodiment of my invention selected by me for purposes of illustration, the construction and operation of which I will now describe.

Referring to these drawings, and particularly to Figs. 2 to 9 thereof, 1 represents the main body of the valve which is preferably made of cast metal of substantially rectangular form in cross section, both horizon-

tally and vertically, and provided on its front side with a circular flange 2, for the attachment of a closing cap or cover of dome shape, indicated at 3, and hereinafter more fully described. Within the main body 1, and preferably cast integrally therewith, is a horizontal partition or wall 4, and a vertical partition or wall 5, the latter being provided with a circular opening 6, surrounded 10 on the outer face of the wall by a valve seat 7. The valve body is also provided with an annular inwardly inclined or sloping flange portion 8 concentric with the valve seat 7, and forming an annular inclined 15 shoulder or support for the flexible diaphragm, hereinafter described. A comparatively narrow passage or chamber, indicated at 9, is thus formed between the vertical wall 5 and the annular flange or shoulder 8, which chamber communicates at its lower 20 end with a larger chamber 10, which I term the flushing chamber, and the valve body is provided at its lower end with a flushing aperture 11, leading from said chamber, the 25 valve body being conveniently provided with a threaded nipple 12, for the attachment of the flushing pipe 13, indicated in Fig. 1, and leading to the closet bowl 14, which may be of any usual or desired construction. It will be noted that the flushing outlet aperture 11 and pipe 13 are of large diameter, to provide a large flow of water from the valve casing.

Within the horizontal and vertical walls 30 or partitions 4 and 5 is formed a second chamber 15, which I term the water inlet chamber, separated from the flushing chamber by said walls, but communicating therewith through the opening 6 and passage 9, 35 controlled by the flushing valve hereinafter described. The valve body is also provided with an outlet aperture 16 of correspondingly large diameter communicating with this water inlet chamber, and adapted to 40 be connected by a pipe 17 with a closed tank 18, shown in Fig. 1, the valve body in this instance having the aperture 16 internally threaded, as shown in the drawings to receive the pipe 17.

Within the water inlet chamber 15 is an auxiliary water inlet chamber 20 formed in any desired manner, as for example, by providing a boss 19 within said chamber 15, with a cored or bored recess or chamber 20, 55 the said auxiliary inlet chamber being arranged concentrically with and opening toward the flushing aperture 6, and having preferably at its rear end a threaded recess 21, which receives the threaded inner end 60 of a hollow transfer tube 22; preferably closed at its outer end and at its inner end, and being provided with a lateral aperture 23 within the auxiliary inlet chamber, and a lateral aperture 24 located at a point sufficiently removed therefrom to communicate

with the back pressure chamber of the valve mechanism hereinafter described, it being understood that this transfer tube extends centrally through the flushing aperture and through the central aperture formed at the 70 inner edge of the inclined annular shoulder 8.

25 represents a flexible diaphragm, preferably of rubber, which is applied at its edges to the annular flange portions 2 of the valve 75 body, and is held in position by the cap 3, which is provided with an annular flange portion 26, engaging the marginal portions of the diaphragm, and being provided preferably with an angular annular flange portion 27 to inclose the peripheral edges of the annular flange 2 of the valve body, and providing a neat finish for the valve mechanism. The cap or cover 3 may be held in position with respect to the main body of 80 the valve in any desired way, as for example, by screws 28, as shown in Figs. 2 and 5. The cap or cover 3 is of dome shape so as to provide a chamber 29, which I term the back pressure chamber, on the outer side 85 of the diaphragm 25, in which the water is accumulated for the purpose of acting upon the diaphragm to close the flushing valve. The cap or cover is also provided with a relief aperture 30 provided in this instance 90 with a valve seat 31 in the form of a ring held in place by a threaded nut 32, and having a conical valve engaging portion, said relief aperture communicating in this instance with a recess 33 which in turn 100 communicates by passage 34 with a short tubular nipple 35 extending through the front wall of the valve body, and through a marginal portion of the diaphragm, and leading into the enlarged flushing chamber 10 of 105 the valve body, communicating with the bowl 14. The recess 33 is provided with a cap or cover 36 held in place by a nut 37. The relief aperture is closed normally by a conical relief valve 38, the stem of which 110 extends through the cap 36 and is provided with a push button 39 or other operating means. The valve stem is actuated in one direction by a spring 40 which normally holds the valve 38 in closed position, and the 115 aperture around the valve stem is made water tight in any desired way, for example, by means of a small diaphragm 41, the marginal portions of which are clamped between the cap 36 and a recess in the wall of the 120 recess 33, and provided with a central opening to fit the valve stem. It will thus be seen that by pressing the button 39 or otherwise actuating the valve stem of the relief valve, the relief valve will be opened, allowing the accumulated water in the pressure chamber 29 to escape through the passage 125 34, and nipple 35, into the large flushing outlet chamber 10 and thence to the bowl.

The hydraulically operated flushing valve 130

is carried by the diaphragm 25 and consists preferably of a rubber ring 42 which engages the valve seat 7, and is preferably carried in a metal shell 43 engaging the inner 5 face of the diaphragm and held in position by a sleeve 44 extending through an aperture in the diaphragm, provided with a flange on the outer face of the diaphragm, and having at its inner end a threaded portion 10 engaged by a nut 45 and washer, for holding the valve proper 42, and shell 43, in proper position with respect to the diaphragm. The sleeve 44 is provided with a central aperture which loosely fits around 15 the transfer tube 22, with an easy fit, so that when the flushing valve is in open position, as shown in Fig. 3, the water which passes through the transfer tube and issues from the lateral aperture 24, can nevertheless seep 20 into the pressure chamber 29. The main water inlet for the valve body is indicated at 50, see Figs. 4 and 7, for example, and communicates directly with the auxiliary water inlet chamber 20 within the boss 19, 25 as clearly shown in Fig. 7, and the valve body may be provided with a threaded aperture or recess, as indicated at 51, to receive the water inlet pipe from the water main, which may be as small as a $\frac{3}{8}$ " pipe, for example, and will usually be of that diameter. 30 It will be seen that as the inlet water enters, instead of passing directly to the inlet chamber 15, it is first received within the auxiliary inlet chamber 20, closely surrounding the transfer tube 22, so that a portion 35 of the water tends to pass through the transfer tube, and to be transferred from the auxiliary inlet chamber to the pressure chamber 29, to build up the required pressure on the outer face of the diaphragm, to 40 close the flushing valve upon its seat 7, and maintain it in closed position. The lateral outlet aperture 24 of the transfer tube is so located, as shown in Fig. 1, that when 45 the valve is in closed position this outlet aperture 24 is outside of the sleeve 44 of the flushing valve, and entirely within the pressure chamber 29, for a purpose which will be hereinafter more fully described, in effecting the final closing of the flushing 50 valve, and in order to secure the proper transfer of water from the water inlet to the pressure chamber under conditions of especially low pressure and volume, so that 55 the device will always operate, even though water is being drawn in some other portion of the dwelling or building. I prefer to provide the sleeve 44 with a throttling device for the auxiliary inlet chamber, to 60 throttle the communication between the auxiliary inlet chamber 20 and the main inlet chamber 15. To this end I provide, as shown in the drawings, an auxiliary throttling sleeve 60 secured to the inner end 65 of the sleeve 44, in such position that when

the flushing valve is closed, it will project into the auxiliary inlet chamber 20, as shown in Fig. 2, while it will be substantially removed from the auxiliary inlet chamber when the flushing valve is open, as clearly shown in Fig. 3, and I prefer to make this throttling sleeve adjustable longitudinally, in order that it may be made to project more or less into the auxiliary inlet chamber and caused to commence its throttling action at an earlier or later period in the closing movement of the valve as may be found to be most desirable with the particular water pressure available where this valve mechanism is installed. To this end 75 the auxiliary throttling sleeve, which surrounds the transfer tube 22, is preferably threaded into the sleeve 44, and secured in its adjusted position by means of a lock nut 61, see Figs. 2 and 3 particularly. I also 80 prefer to provide the inner extremity of the throttling tube 60 with an annular flange 62 of greater diameter than the sleeve itself, but of less diameter than the interior of the auxiliary water inlet chamber 20, to further 85 the throttling operation, and in some cases the diameter of this outwardly extending flange 62 may be varied by filing it away slightly, all the way around, or by filing notches in it, at the time that the valve 90 mechanism is installed, in case it should be found that it affects too great a throttling operation with the particular water pressure available. The water inlet pipe from the main to the water inlet aperture 50, which 95 is indicated at 70 in Fig. 1, is provided with an auxiliary cut off cock, indicated at 71, adjacent to the valve mechanism, so that the water supply to the valve may be cut off when it is desired, to clean, adjust, or 100 inspect the valve mechanism, and also for another purpose hereinafter described. 105 The parts being constructed and arranged as shown in the drawings, and the valve mechanism being connected to the water 110 supply pipe 70, to the closet bowl 14, and to the tank 18, the operation will be as follows. As the water enters from the main through pipe 70, it will enter the auxiliary inlet chamber 20, and assuming that the 115 flushing valve is in open position, as shown in Fig. 3, part of the water will pass through the flushing orifice 6 to the bowl, filling the water seal, while a portion of the water will be transferred by the transfer pipe 22 to the pressure chamber, the relief valve 38 of which is closed. As the water accumulates in the pressure chamber 29, it will act upon the outer face of the diaphragm 25, which is of much larger area 120 than the flushing valve, and will move the flushing valve toward its closed position, gradually closing the flushing orifice 6, and at the same time forcing the throttling sleeve 60 into the auxiliary water chamber 125 130

4

20. The action of this throttling sleeve tends to prevent the free access of water from the auxiliary inlet chamber to the main inlet chamber 15, and cause it to be transferred more rapidly through the transfer tube to the pressure chamber, and as the flushing valve approaches its closed position, the outlet aperture 24 in the side wall of the transfer tube will be uncovered, 50 as will be seen by reference to Fig. 2, thereby permitting a more rapid transfer of water to the back pressure chamber 29, and causing the last portion of the closing movement to be effected more rapidly and firmly than the earlier portion of the closing movement, and insuring the tight closing of the valve. This effect is produced by the combined action of the throttling sleeve on the one hand, and on the other, the uncovering 55 of the discharge aperture 24 of the transfer tube by the gradual inward movement of the flushing valve. As soon as the flushing valve is closed, all communication between the water inlet chamber and the bowl is prevented. The water, however, continues to flow in through the main into the auxiliary inlet chamber 20, and thence into the main inlet chamber 15, and thence by pipe 17 into the tank 18, where it accumulates, 60 compressing air in the tank until the pressure of the air becomes equal to the pressure per square inch of the water in the main pipe 70 communicating therewith. There is, therefore, accumulated in the tank, a large volume of water communicating with the valve mechanism, by the pipe 17 of large diameter, which is valuable for flushing purposes, while supplied by the small pipe 71 from the main under comparatively 65 low pressure.

40. When it is desired to flush the bowl, it is only necessary to open the relief valve 38 which has no connection whatever with the flushing valve. The opening of the relief valve establishes communication between the back pressure chamber 29 and the flushing outlet chamber 10, which is of large diameter, and immediately reduces the pressure in the back pressure chamber, so that the accumulated pressure in the tank and main, and in the main and auxiliary water inlet chambers, acting on the rear face of the flushing valve, causes the flushing valve to open to its full extent, and expel the water 50 in the back pressure chamber quickly. The accumulated water in the tank 18 thus flows through the pipe 17 and main inlet chamber 15, and through the flushing outlet 6 and flushing chamber 10 to the bowl, effecting a 55 thorough, rapid, and powerful flushing of the bowl with the water accumulated in the tank. As this flushing action reduces the pressure opposed to the water in the inlet pipe 70 or main, water immediately commences to flow through the main into the auxiliary inlet chamber, the parts then being in the position indicated in Fig. 3, the incoming water joining in the flushing action, a portion being transferred through the transfer tube 22, and seeping slowly 70 through the aperture 24 and between the tube and the sleeve 44 into the back pressure chamber, the relief valve 38 having in the mean time been closed by releasing the push button or other actuating means. 75 Pressure immediately begins to accumulate in the back pressure chamber and the flushing valve begins to close. The flushing action will take place rapidly until checked by the partial closing of the valve, after which the valve will close more slowly, permitting a portion of the incoming water to trickle through the outlet 6 to the bowl, to effect what is termed the after-fill, and insure the bowl and water seal receiving the necessary amount of water after the flushing action, and the closing action of the valve will continue slowly as the pressure builds up in the pressure chamber 29, until the valve 42 is almost seated, at which time 80 the outlet aperture 24 of the transfer tube will be uncovered and permit it to transfer more rapidly into the pressure chamber to insure the final seating of the valve. As before stated, the throttling tube cooperates in 85 effecting the transfer of water from the auxiliary water inlet chamber 20 to the back pressure chamber. The effect of the uncovering of the outlet aperture 24 of the transfer tube before the valve is completely seated, effects the quick and positive final closing of the valve, and obviates the hissing noise frequently made in the final throttling action of a valve in closing off the supply of water. 90 As soon as the flushing valve is completely seated, effects the quick and positive final closing of the valve, and obviates the hissing noise frequently made in the final throttling action of a valve in closing off the supply of water. As soon as the flushing valve 95 has closed water immediately accumulates in the tank 18 from which it has been partially or wholly withdrawn by the flushing action, depending upon the duration of flushing, which may be controlled with 100 great accuracy and precision, by adjusting the throttling sleeve 60 in the manner before described, and the parts return to normal position indicated in Fig. 2 and remain in this position until the valve mechanism 105 is again operated. It will be seen that the flushing valve itself is operated entirely by hydraulic means independent of the operator, and therefore cannot be injured or interfered with by the operator, who can only 110 actuate the relief valve of the pressure chamber.

115. It frequently happens in the use of flushing valves in which a closed tank is employed, that a considerable portion of the air compressed in the tanks is gradually absorbed in the water, so that if the tank is not completely emptied at each flushing operation, the amount of air in the tank becomes 120 reduced until there is no longer sufficient air 130

present to perform the function of an air cushion on the upper surface of the water. In such case, it is desirable to completely empty the tank and allow the tank to fill with air in order to restore the parts to their original condition and efficiency. To this end the auxiliary cut off valve 71 performs an important function. By closing this valve and shutting off communication with the inlet pipe 70 and water main, and then actuating the relief valve 38 of the back pressure chamber, the flushing action will take place as heretofore described, and as no water is permitted to enter the valve mechanism, the auxiliary cut off valve 71 being closed, no water will accumulate within the back pressure chamber to effect the closing of the flushing valve, hence all the water will run out of the tank, establishing a free communication with the atmosphere through the bowl, and permitting the tank 18 to refill with air, after which the auxiliary cut off valve 71 is opened and the incoming water will close the flushing valve and refill the tank until the air therein is compressed, so as to balance the water pressure in the main, as before described.

It will be seen that the fact that the incoming water enters the auxiliary water inlet chamber closely surrounding the transfer tube 22, and is further throttled at the exit of the auxiliary water inlet chamber during a portion of the closing movement of the valve, insures that even under conditions of small volume and low pressure of the water supply, sufficient incoming water will be transferred to the back pressure chamber at all times, and under all circumstances, to secure the accurate and efficient closing of the flushing valve after the flushing operation, and the accumulation of the supply of water for the next flushing operation in the tank, must necessarily follow. My improved valve mechanism can therefore be installed and efficiently operated in any ordinary dwelling house or other building or location, no matter how small the volume of the water supply thereto may be.

While I prefer to employ the hollow transfer tube 22 hereinbefore described, it will be understood that there is formed an annular passage of very small area between the exterior of the tube and the interior of the sleeve 44, and the throttling sleeve 60 through which small quantities of water may pass, owing to the looseness of fit, and in some instances I may employ in place of the transfer tube 22, a solid pin 22^a as shown in Fig. 10, and depend upon the annular passage between the interior of the pin and the interior of the sleeves 44 and 60 to transfer the necessary water to the pressure chamber. I prefer, however, to employ the transfer tube 22

constructed and operating as hereinbefore described. I also prefer in either case to slightly reduce the outer end of the transfer tube or the pin as the case may be, to provide a portion 22^b of smaller diameter than the pin or tube which can be grasped by a pair of pliers or other suitable device in screwing in the tube or pin, so as not to bore the surface over which the sleeve 44 moves.

What I claim and desire to secure by Letters Patent is:—

1. In a hydraulically operated flushing valve mechanism, the combination with a valve body provided with a water inlet, a tank aperture, a flushing discharge aperture, a flushing valve interposed between the tank aperture and discharge aperture, a pressure chamber for closing the valve and holding it normally in closed position, a relief valve for said pressure chamber, said flushing valve being provided with an aperture extending therethrough, and a stationary part secured to the valve body and extending loosely through said aperture, of a water inlet chamber, of small diameter within the valve body, communicating with said water inlet, and closely surrounding said stationary part, and having a discharge aperture adjacent to the flushing valve in communication with the tank aperture, and a throttling device carried by said valve, and partially closing the discharge aperture of said water inlet chamber when the flushing valve is in closed position, to facilitate the transfer of a portion of the water from the water inlet chamber to the pressure chamber.

2. In a hydraulically operated flushing valve mechanism, the combination with a valve body provided with a water inlet, a tank aperture, a flushing discharge aperture, a flushing valve interposed between the tank aperture and discharge aperture, a pressure chamber for closing the valve and holding it normally in closed position, a relief valve for said pressure chamber, said flushing valve being provided with an aperture extending therethrough, and a stationary part secured to the valve body and extending loosely through said aperture, of a water inlet chamber of small diameter within the valve body, communicating with said water inlet, and closely surrounding said stationary part, and having a discharge aperture adjacent to the flushing valve in communication with the tank aperture, and a throttling device carried by said valve, and partially closing the discharge aperture of said water inlet chamber when the flushing valve is in closed position, to facilitate the transfer of a portion of the water from the water inlet chamber to the pressure chamber, and means for adjusting said throttling device with respect to the flushing valve, to vary its position, with respect to the inlet chamber,

and cause its throttling action to commence at an earlier or later stage in the closing movement of the flushing valve.

3. In a hydraulically operated flushing valve mechanism, the combination with a valve body provided with a water inlet, a tank aperture, a flushing discharge aperture, a flushing valve interposed between the tank aperture and discharge aperture, a pressure chamber for closing the valve and holding it normally in closed position, and a relief valve for said pressure chamber, said flushing valve being provided with an aperture extending therethrough, of a stationary transfer tube extending through said aperture in the flushing valve, and being provided with a discharge aperture in its side wall within said pressure chamber, adapted to be covered by the wall of said aperture when the flushing valve is in open position, a water inlet chamber of small diameter communicating with the water inlet, surrounding said transfer tube, and communicating therewith, and having a discharge aperture adjacent to the flushing valve, in communication with the tank aperture and concentric with said transfer tube and sleeve, and a tubular throttling device carried by said sleeve, and adjustable longitudinally with respect thereto, to vary the stage in the closing movement of the valve at which its throttling action shall take place.
4. In a hydraulically operated flushing valve mechanism, the combination with a valve body provided with a water inlet, a tank aperture, a flushing discharge aperture, a flushing valve interposed between the tank aperture and discharge aperture, a pressure chamber for closing the valve and holding it normally in closed position, and a relief valve for said pressure chamber, said flushing valve being provided with a sleeve extending therethrough, of a stationary transfer tube secured to the valve body extending through said sleeve into the pressure chamber, and provided with a discharge aperture in its side wall, opening into the pressure chamber when the valve is in closed position, and adapted to be covered by said sleeve when the flushing valve is in open position, an inlet chamber of small diameter communicating with the water inlet, surrounding said transfer tube, and communicating therewith, and having a discharge aperture adjacent to said flushing valve, in communication with the tank aperture and concentric with said transfer tube and sleeve, and a tubular throttling device carried by said sleeve, and adapted to partially close the said discharge aperture of said inlet chamber when the valve is in closed position, to facilitate the passage of water from the inlet chamber to the pressure chamber.

5. In a hydraulically operated flushing valve mechanism, the combination with a valve body provided with a water inlet, a

tank aperture, a flushing discharge aperture, a flushing valve interposed between the tank aperture and discharge aperture, a pressure chamber for closing the valve and holding it normally in closed position, and a relief valve for said pressure chamber, said flushing valve being provided with a sleeve extending therethrough, of a stationary transfer tube secured to the valve body extending through said sleeve into the pressure chamber, and provided with a discharge aperture in its side wall, opening into the pressure chamber when the valve is in closed position, and adapted to be covered by said sleeve when the flushing valve is in open position, an inlet chamber of small diameter communicating with the water inlet, surrounding said transfer tube, and communicating therewith, and having a discharge aperture adjacent to said flushing valve, in communication with the tank aperture and concentric with said transfer tube and sleeve, and a tubular throttling device carried by said sleeve, and adjustable longitudinally with respect thereto, to vary the stage in the closing movement of the valve at which its throttling action shall take place.

6. In a hydraulically operated flushing valve, the combination with a valve body provided with a main water inlet chamber having a tank outlet, a flushing chamber having a flushing outlet, a partition separating said chambers and provided with a flushing aperture having a valve seat, a pressure chamber, a diaphragm forming a wall of the pressure chamber, a valve connected to said diaphragm, and normally engaging said seat, and a relief valve for said pressure chamber, of an auxiliary inlet chamber of small diameter within the main inlet chamber, a water inlet connected therewith, said auxiliary inlet chamber having a discharge aperture adjacent to the flushing valve, communicating with the main inlet chamber, a transfer tube secured to the valve body, concentrically with the auxiliary inlet chamber, communicating therewith, and extending through an aperture in the flushing valve, and having a discharge aperture, communicating with the pressure chamber, and a throttling device carried by the flushing valve, and partially closing the discharge aperture of said auxiliary inlet chamber, when the flushing valve is in closed position.

7. In a hydraulically operated flushing valve, the combination with a valve body provided with a main water inlet chamber having a tank outlet, a flushing chamber having a flushing outlet, a partition separating said chambers and provided with a flushing aperture having a valve seat, a pressure chamber, a diaphragm forming a wall of the pressure chamber, a valve connected to said diaphragm, and normally engaging

10 said seat, and a relief valve for said pressure chamber, of an auxiliary inlet chamber of small diameter within the main inlet chamber, a water inlet connected therewith, said auxiliary inlet chamber having a discharge aperture adjacent to the flushing valve, communicating with the main inlet chamber, a transfer tube secured to the valve body concentrically with the auxiliary inlet chamber, communicating therewith, and extending through an aperture in the flushing valve, and having a discharge aperture, in its side wall within the pressure chamber, adapted to be covered when the flushing valve is in open position, and an adjustable throttling sleeve carried by said flushing valve, arranged concentrically with the transfer tube, and the discharge aperture of said auxiliary inlet chamber, and partially closing said discharge aperture when the valve is in closed position.

15 8. In a hydraulically operated flushing valve mechanism of the kind described, the combination with a valve body provided with a tank aperture, of relatively large area, a flushing discharge aperture of correspondingly large area, a normally closed flushing valve interposed between the tank aperture and flushing aperture, a pressure chamber for closing the flushing valve and maintaining it in closed position, and a relief valve for said pressure chamber, of a stationary part extending loosely through an aperture in said flushing valve, a water inlet chamber of small diameter, surrounding said stationary part, and having a discharge aperture of relatively small area, communicating with the tank aperture, to facilitate the transfer of water to the pressure chamber.

20 9. In a hydraulically operated flushing valve mechanism of the kind described, the combination with a valve body provided with a tank aperture of relatively large

area, a flushing discharge aperture of correspondingly large area, a normally closed flushing valve interposed between the tank aperture and flushing aperture, a pressure chamber for closing the flushing valve and maintaining it in closed position, and a relief valve for said pressure chamber, of a stationary part extending loosely through an aperture in said flushing valve, a water inlet chamber of small diameter surrounding said stationary part, and having a discharge aperture of relatively small area, communicating with the tank aperture, to facilitate the transfer of water to the pressure chamber.

25 10. In a hydraulically operated flushing valve mechanism of the kind described, the combination with a valve body provided with a tank aperture of relatively large area, a flushing discharge aperture of correspondingly large area, a normally closed flushing valve interposed between the tank aperture and flushing aperture, a pressure chamber for closing the flushing valve and maintaining it in closed position, and a relief valve for said pressure chamber, of a stationary part extending loosely through an aperture in said flushing valve, a water inlet chamber of small diameter surrounding said stationary part, and having a discharge aperture of relatively small area communicating with the tank aperture, to facilitate the transfer of water to the pressure chamber, and adjustable means for throttling the discharge aperture of said inlet chamber.

30 In testimony whereof I affix my signature.

PHILIP HAAS.
